CLAIM

The ornamental design for an earphone, as shown and described.

DESCRIPTION

FIG. 1 is a front elevational view of an earphone, showing my new design.

FIG. 2 is a rear elevational view thereof.

FIG. 3 is a left side elevational view thereof.

FIG. 4 is a right side elevational view thereof.

FIG. 5 is a top plan view thereof.

FIG. 6 is a bottom plan view thereof.

FIG. 7 is a perspective view thereof; and,

FIG. 8 is an exploded view thereof, showing a top portion separated from a bottom portion of the earphone.

The dash-dash broken lines shown in FIG. 8 depict portions of the earphone that form no part of the claimed design. The dot-dot-dash broken lines shown in FIG. 6 depict a boundary to the claim and form no part of the claimed design.
